GAME BOARD

Joseph E. Mitchell, 435 Orleans Ave.,
Long Beach, Calif. 90814

Filed Apr. 7, 1969, Ser. No. 16,612

Term of patent 14 years

U.S. Cl. D34—5   Int. Cl. D21—01

FIG. 1

FIG. 2

FIG. 3

FIG. 1 is a top perspective view showing my ornamental design for a game board;

FIG. 2 is an end view of the same; and

FIG. 3 is a side view of the same.

The depressed cube in the figures illustrates the position of one cube just before it may be ejected from the unit.

I claim:

The ornamental design for a game board, as shown and described.
